BY *John Albershein.*
ATTORNEY.

UNITED STATES PATENT OFFICE.

HARRY MINTZER, OF PHILADELPHIA, PENNSYLVANIA, ASSIGNOR OF ONE-HALF TO W. HOWARD METCALF, OF SAME PLACE.

DESIGN FOR A SHUTTER BOWER AND FASTENER.

SPECIFICATION forming part of Design No. 23,423, dated July 3, 1894.

Application filed May 31, 1894. Serial No. 513,084. Term of patent 7 years.

To all whom it may concern:

Be it known that I, HARRY MINTZER, a citizen of the United States, residing in the city and county of Philadelphia, State of Pennsylvania, have invented and produced a new and original Design for a Shutter Bower and Fastener, of which the following is a specification, reference being had to the accompanying drawing, forming part thereof.

- The leading feature of my design for a shutter bower and fastener is a bar with segmental shaped pieces, and necks between the same.

In the drawing: A designates a bar, on the edge of which are segmental shaped pieces B, 15 B, which curve toward each other as at C, and have recesses D between the same.

E designates necks which join said pieces B.

What I claim is—

The design for a shutter bower and fastener, substantially as shown and described.

HARRY MINTZER.
